UNITED STATES PATENT OFFICE.

OSCAR L. NEISLER, OF INDIANAPOLIS, INDIANA.

COMBINED LATCH AND LOCK.

SPECIFICATION forming part of Letters Patent No. 334,887, dated January 26, 1886.

Application filed March 30, 1885. Serial No. 160,572. (No model.)

To all whom it may concern:

Be it known that I, OSCAR L. NEISLER, a citizen of the United States, residing at Indianapolis, in the county of Marion and State 5 of Indiana, have invented a new and useful Combined Latch and Lock, of which the following is a specification.

My invention relates to an improvement in that class of door-latches in which the parts 10 are moved by the force of gravitation.

The object of my improvement is to provide a door-latch of few parts adapted to be operated by a knob and spindle, which latch may be locked in position or used independently 15 of the lock.

The accompanying drawings illustrate my invention.

Figure 1 is an elevation showing the position of the parts when used as a latch alone. 20 Fig. 2 is a similar elevation showing the position of the parts when used as a lock.

A is a sliding latch-bolt having lugs b b, which engage the arms of the tumbler e, through which the knob-spindle passes in the 25 usual manner.

C is a bent lever pivoted to the lock-case at d. One arm of said lever engages the sliding latch-bolt and the other is weighted, the purpose being to force the latch outward by the 30 force of gravitation. The latch is drawn inward by the partial rotation of the tumbler e, the inward movement of the latch-bolt raising the weighted arm of the bent lever C.

For the purpose of locking the latch-bolt so 35 as to prevent its inward movement, lever C is provided with a projection, f, which is engaged when the latch-bolt is thrown outward by the gravity catch-bar h. Said catch-bar is pivoted to the lock-case at i, and the disposi-

tion of its weight is such that it will assume 40 normally the position shown in Fig. 2, thereby preventing the upward movement of the weighted arm of lever C. The catch-bar h may be disengaged from lever C by raising its outer end by means of the arm j, which projects through the lock-case, or by means of a key working in the key-hole k.

For the purpose of keeping catch-bar h out of engagement with lever C, when it is desirable to use the latch without locking, a swinging 50 stop, l, is pivoted to the lock-case at m. When the outer end of h is raised so that its hooked end is clearly disengaged from lever C, a projection, n, on the catch is engaged by stop l. The combined length of the stop l and the 55 catch-bar from n to the center is a little greater than the distance between the pivots m and i, so that some force is required to cause the end of stop l to pass downward past a line drawn from the center of one pivot to the other. 60

When it is desired to lock the catch h, so that it cannot be raised by the key, stop l is swung into the position indicated by dotted lines, Fig. 2.

I claim as my invention—
65
In a combined latch and lock, the combination, with the lock-case, the sliding bolt A, the weighted lever C, and the gravity catch-bar h, adapted to engage and to hold in position said lever and having the projection n, of the 70 swinging stop l, adapted to engage said catch-bar, in the manner and for the purpose specified.

OSCAR L. NEISLER.
